(57) **CLAIM**

We claim the ornamental design for grenade launcher, as shown and described.

DESCRIPTION

FIG. 1 is a perspective view of a grenade launcher according to an embodiment of the invention.

FIG. 2 is a right side view of the grenade launcher depicted in FIG. 1.

FIG. 3 is a front view of the grenade launcher depicted in FIG. 1.

FIG. 4 is a rear view of the grenade launcher depicted in FIG. 1.

FIG. 5 is a left side view of the grenade launcher depicted in FIG. 1.

FIG. 6 is a top view of the grenade launcher depicted in FIG. 1; and,

FIG. 7 is a bottom view of the grenade launcher depicted in FIG. 1.

Items shown in broken lines are for illustrative purposes only and form no part of the claimed invention.

1 Claim, 4 Drawing Sheets
